UNITED STATES PATENT OFFICE.

JOSEPH DEUBEL, OF CLIFTON, NEW JERSEY.

TOBACCO-SHREDDING APPARATUS.

1,403,489.

Specification of Letters Patent. Patented Jan. 17, 1922.

Application filed February 19, 1921. Serial No. 446,215.

To all whom it may concern:

Be it known that I, JOSEPH DEUBEL, a citizen of the United States, and a resident of Clifton, county of Passaic, and State of New Jersey, have invented certain new and useful Improvements in Tobacco-Shredding Apparatus, of which the following is a specification.

My improvements relate especially to the shredding and reducing of remnants of tobacco leaf for use as filling material or analogous purposes in the art of preparing tobacco for commercial purposes, and the main object of my invention is to afford simple, inexpensive, but effective apparatus adapted for the purpose in which the use of knives is dispensed with, and provision is made for effectually regulating and grading the product.

To this end the invention consists in the specific combination and arrangement of parts and appliances described and claimed; —distinctive features consisting in the use of a series of rotatable discs carrying peripheral disintegrating pins and lateral disintegrating pins protuberant from either side thereof, in conjunction with stationary discs on which are positioned retardant studs which intervene between the said lateral disintegrating pins on the rotatable discs, by which means the tobacco is ripped and torn apart and reduced to fragments; in the provision made for screening and grading the product, and in this connection, in the use of a screen for this purpose in which provision is made for adjusting the area of the outlets while maintaining the prescribed square shape thereof; and in the use of air exhaust means for withdrawing the product, when suitably reduced, through said screen, and discharging it from the apparatus; the invention also including certain minor details of construction, all as hereinafter fully set forth.

In the accompanying drawings,

Fig. 1, is an end view of apparatus embodying the essential features of my invention, the casing being broken away in part and shown in section for convenience of illustration;

Fig. 2, is a central vertical section taken upon plane of line 2—2, Fig. 8;

Fig. 3, is a top view of the apparatus, the casing being broken away in part to show the operative parts in central horizontal section;

Fig. 4, is a vertical section taken upon plane of line 4—4, Fig. 3;

Fig. 5, is a side elevation with the casing removed, showing one of the adjustable grading screens;

Fig. 6, is an elevation of a portion of one of the grading screens, illustrating the adjustment of the area of the outlets;

Fig. 7, is a section of the grading screen shown in Figs. 5 and 6, taken upon plane of line 7—7, Fig. 6;

Fig. 8, is a side elevation of the exterior of the apparatus, the casing, etc., being broken away in part.

Rigidly mounted upon and between parallel horizontal members F, F, of a suitable frame work is a basic skeleton shell consisting of end discs b, b, connected by a bottom member b', on which latter are intermediate discs or partitions b², b². In the construction shown in the drawings two of these intermediate partitions b², b², (Fig. 3) are provided, although one or any plural number thereof may be incorporated in the apparatus, according to the requisite size and capacity thereof. The end discs b, b, are formed with external bearing extensions b', b'', in which is journalled a rotatable shaft S, upon one extremity of which is rigidly mounted a driving pulley S', as shown more particularly in Figs. 1, 3 and 5, of the drawings.

Mounted upon and between the end discs b, b is a rectangular frame C, (Figs. 2, 4 and 5) having end members c, c, concentric with and fitting upon the upper edges of said end discs b, b, and also formed with longitudinal side members c', c'. On this rectangular frame C, is mounted the hopper H, arranged to deliver tobacco through the opening C', (Fig. 4) in said frame C, to the disintegrating cylindrical chamber D. The latter is formed between the end discs or members b, b, of the skeleton shell, referred to, and contains the stationary partitions b², b², which subdivide said disintegrating chamber into compartments.

Rigidly mounted on the shaft S, within the disintegrating chamber D, and between the intermediate discs or partitions b², b², are spider hubs s, s, formed with equidistant radial arms s', s', as shown more particularly in Fig. 3. Rigidly protuberant from the ends of the spider arms s', s', are disintegrating pins s², s², and also rigidly protuberant from the sides of said spider

arms s' , s' , are lateral disintegrating pins s^3 , s^3 , so positioned as to intervene between concentric rows of retardant studs b^x , b^x , rigidly protuberant from the fixed partitions b^2 , b^2 , and the end discs b , b , as will be seen by reference more particularly to Figs. 2, 3 and 4, of the drawings.

The cylindrical side walls of the disintegrating chamber D , are formed of approximately semi-cylindrical plates d , d , secured as shown in Fig. 3, to the end discs b , and to the intermediate discs b^2 . These wall plates d , d , extend from the bottom member b' , of the skeleton frame to the longitudinal members c' , c' , of the rectangular top frame C , as shown more particularly in Fig. 4. Each wall plate d , d , is formed with a series of outlet apertures d' , d' , of square shape and uniform area, as shown particularly in Figs. 5 and 6, constituting a screen through which the tobacco passes when sufficiently reduced for the purpose.

Fitting upon the peripheral surfaces of these wall side plates d , d , are supplementary screen plates A , A , mounted adjustably with relation thereto and also formed with corresponding series of outlet apertures a , a , which may be brought into coincidence with those $(d'$, d') in said interior wall side plates d , d , as shown, for instance, in Figs. 2, 4 and 5, of the drawings.

These adjustable screen plates A , A , are formed with end flanges or extensions a' , a' , which overlap the portions d^2 , d^2 , of the side wall plates d , d , which are rigidly attached to the extensions b^2 , b^2 , of the end discs b , b , as shown more particularly in Figs. 3 and 8. The flanges a' , a' , are formed with diagonal slots a^2 , a^2 , (i. e., slots positioned at an angle of 45° as related to the longitudinal axis of the shaft S) for the accommodation of the studs d^4 , d^5 , protuberant from the said extensions d^2 , d^2 , of the side wall plates d , d , the studs d^5 , being screw threaded for the reception of binding nuts d^6 , d^6 , as shown in Figs. 1, 5, 6 and 8. When the nuts d^6 , d^6 , are loosened, the auxiliary screen plates A , A , may be shifted on the side wall screen plates d , d , to regulate the available area of exit for the reduced tobacco leaf, the adjustment being effected diagonally as related to the apertures d' , a , and to the longitudinal axis of the apparatus, so that the said available area will always be square in configuration. For instance, in all but Fig. 6, of the drawings the auxiliary screen plates A , A , are shown as positioned to afford a maximum of outlet area, with the studs d^4 , d^5 , at the upper ends of the diagonally inclined slots a^2 , a^2 , whereas in said Fig. 6, the auxiliary screen plates A , A , are positioned to afford a minimum area of exit for the disintegrated tobacco, the studs d^4 , d^5 , being at the bottom of the diagonal slots a^2 , a^2 .

By thus regulating the area of the exit apertures for the products of the disintegrating chamber without altering the shape of said exit apertures, I attain uniformity in the size of product withdrawn, because the relative proportions of the edges of the exit apertures are always the same,—i. e., as broad as long. Obviously this result could not be attained by the use of round, oval or other shaped apertures, and hence my diagonal adjustment of the square holed supplementary screen plates A , A , in conjunction with the square holed fixed side plates d , d , is an important factor in adapting the apparatus to the production of different grades of tobacco, each composed of fragments uniform in size.

An induced current of air is used as the vehicle for the withdrawal of the disintegrated tobacco from the apparatus through the medium of a partial vacuum created in the casing by any appropriate means, as by the exhaust fans e , e , shown in Fig. 1, as positioned to exhaust air from the casing K , through the neck k , thereof. In the arrangement shown the blades of the fans e , e , are pitched in opposite directions so as to withdraw the air and lighter particles of leaf tobacco carried thereby through the axial apertures k' , k' , and to discharge same through the spouts k^2 , k^2 , although I do not limit myself to this method or means, since other well known mechanical expedients may obviously be resorted to with like effect, and without departing from the spirit and intent of my invention in this respect.

In the operation of my apparatus the radially peripheral pins s^2 , on the spider hubs s , are of assistance in positively dragging the leaf tobacco into the disintegrating chamber D , from the hopper H , and distributing such supply of raw material to the concentric rows of fixed retardant studs b^x , and intervening lateral disintegrating pins s^3 , s^3 , and also in insuring a circulation of material through said chamber and between said retardant studs b^x , and disintegrating pins s^3 , until sufficiently reduced for passage through the exit apertures d' , a , of the side screens d , A , as will be understood by reference particularly to Figs. 2, 3 and 4, of the drawings.

As heretofore intimated, the lighter portions of the tobacco leaf treated are drawn off, when sufficiently reduced in size, through the neck k of the casing. The stems and heavier refuse portions of the product withdrawn from the disintegrating chamber D , fall by gravity from the air vehicle to the bottom of the casing K , and through the discharge opening L^2 , shown in Figs. 1 and 4.

My apparatus is simple and comparatively inexpensive both in construction and operation, and of a strong substantial character well adapted to endure the strain to which the parts are subjected in the twisting, tear-

ing and disintegration of tobacco leaf, the fibre and stems of which are tough and tenacious. Furthermore I dispense entirely with the use of rollers and reduction knives, 5 which cut the tobacco up unevenly and create waste, besides which the knives soon get out of order and have to be replaced, whereas my retardant and disintegrating pins are not injured by nails and any other foreign matter 10 frequently encountered in the ordinary tobacco leaf supply. The absence of gearing in my apparatus is also to be noted,—only a single rotatable shaft being employed in connection with the disintegrating chamber, in 15 which latter the leaf tobacco is ripped and torn apart, in contradistinction to the old method of reduction by cutting.

What I claim as my invention and desire to secure by Letters Patent is,

20 1. Tobacco shredding apparatus of the character designated, comprising a cylindrical disintegrating chamber having end discs and medial fixed partitions, concentric series of laterally protuberant rigid retardant 25 studs on the said end discs and the said medial partitions of the disintegrating chamber, a power shaft mounted axially as related to said disintegrating chamber and extending therethrough, spider hubs mount- 30 ed rigidly on said power shaft and positioned between said end discs and said fixed medial partitions, laterally protuberant dis- 35 integrating pins on the radial arms of said spider hubs positioned to intervene between the said concentric rows of fixed retardant studs on the end discs and medial partitions, exit screens incorporated in the sides of said disintegrating chamber, a hopper positioned to feed tobacco leaf to said disinte- 40 grating chamber, a casing enclosing the main portion of said disintegrating chamber, and means for exhausting air from said casing, for the purpose described.

2. Tobacco shredding apparatus of the 45 character designated, comprising a cylindrical disintegrating chamber having end discs and medial fixed partitions, concentric series of laterally protuberant rigid retardant studs on the said end discs and the said 50 medial partitions of the disintegrating chamber, a power shaft mounted axially as related to said disintegrating chamber and extending therethrough, spider hubs mount- 55 ed rigidly on said power shaft and positioned between said end discs and said fixed medial partitions, peripherally protuberant dis- 60 integrating pins on the ends of the radial arms of said spider hubs and laterally protuberant disintegrating pins on the sides of said radial spider arms positioned to intervene between the said concentric rows of 65 fixed retardant studs on the end discs and medial partitions, exit screens incorporated in the sides of said disintegrating chamber, a hopper positioned to feed tobacco leaf to

said disintegrating chamber, a casing enclosing the main portion of said disintegrating chamber, and means for exhausting air from said casing, for the purpose described.

3. Tobacco shredding apparatus of the character designated, comprising a cylindrical disintegrating chamber having end discs and medial fixed partitions, concentric series of laterally protuberant rigid retardant 70 studs on the said end discs and the said medial partitions, a power shaft mounted axially as related to the said disintegrating chamber and extending therethrough, spider hubs mounted rigidly on said power shaft 75 and positioned between said end discs and said fixed medial partitions, laterally protuberant disintegrating pins on the radial arms of said spider hubs positioned to intervene between the said concentric rows of 80 fixed retardant studs on the end discs and medial partitions, fixed exit screens constituting in part the side walls of said disintegrating chamber, supplementary exit screens fitting over and upon said fixed side 85 wall screens and mounted adjustably with relation thereto, a hopper positioned to feed tobacco leaf to said disintegrating chamber, a casing enclosing the main portion of said disintegrating chamber, and means for exhausting air from said casing, for the purpose described.

4. Tobacco shredding apparatus of the character designated, comprising a cylindrical disintegrating chamber having end discs and medial fixed partitions, concentric series of laterally protuberant rigid retardant studs on the said end discs and the said medial partitions, a power shaft mounted axially as related to the said disintegrating 100 chamber and extending therethrough, spider hubs mounted rigidly on said power shaft and positioned between said end discs and said fixed medial partitions, laterally protuberant disintegrating pins on the radial arms of said spider hubs positioned to intervene between the said concentric rows of fixed retardant studs on the end discs and medial partitions, exit screens incorporated in the sides of said disintegrating chamber, a hopper positioned to feed tobacco leaf to said disintegrating chamber, a casing enclosing the main portion of said disintegrating chamber, and means for exhausting air from said casing, for the purpose described.

5. Tobacco shredding apparatus of the character designated, comprising a cylind-

- drical disintegrating chamber having end discs and medial fixed partitions, concentric series of laterally protuberant rigid retardant studs on the said end discs and the said 5 medial partitions, a power shaft mounted axially as related to the said disintegrating chamber and extending therethrough, spider hubs mounted rigidly on said power shaft and positioned between said end discs and 10 said fixed medial partitions, laterally protuberant disintegrating pins on the radial arms of said spider hubs positioned to intervene between the said concentric rows of fixed retardant studs on the end discs and 15 medial partitions, fixed exit screens constituting in part the side walls of said disintegrating chamber and formed with series of square shaped apertures of uniform area, supplementary exit screens fitting over and 20 upon the peripheral surfaces of said fixed wall screens and mounted adjustably with relation thereto, and also formed with series of square apertures of the same area and duplicating those on said fixed side screens, 25 a hopper positioned to feed leaf tobacco to said disintegrating chamber, a casing enclosing the main portion of said disintegrating chamber, and means for exhausting air from said casing, for the purpose described 30 6. In tobacco shredding apparatus of the character designated, the combination with the disintegrating chamber having fixed side wall screens formed with square exit apertures, of supplementary screen plates fitting 35 upon and over the peripheral surfaces of said side wall screens and formed with square exit apertures duplicating those on said fixed side wall screens and means for adjusting said supplementary screen plates diagonally upon and 40 with relation to said fixed side wall screens, for the purpose described. 7. Tobacco shredding apparatus of the character designated, comprising a cylindrical disintegrating chamber having end discs and medial fixed partitions, concentric series of laterally protuberant rigid retardant studs on the end discs and the said medial partitions, a power shaft mounted axially as related to the said disintegrating 45 chamber and extending therethrough, spider hubs mounted rigidly on said power shaft and positioned between said end discs and said fixed medial partitions, laterally protuberant disintegrating pins on the radial arms of said spider hubs positioned to intervene between the said concentric rows of 50 fixed retardant studs on the end discs and medial partitions, fixed exit screens constituting in part the side walls of said disintegrating chamber and formed with series of square apertures of uniform area, supplementary exit screens fitting over and upon the peripheral surfaces of fixed side wall screens, means for adjusting said supplementary exit screens diagonally upon and 55 with relation to said fixed side wall screens, a hopper positioned to feed leaf tobacco to said disintegrating chamber, a casing enclosing the main portion of said disintegrating chamber and screens, the upper part of said casing being formed with a discharge neck for the lighter products and the lower portion of the casing with a discharge opening for the heavier products, and means for exhausting air from said casing through the discharge neck in the upper portion thereof, for the purpose described.
